UNITED STATES PATENT OFFICE.

CHARLES LOUIS COUVRETTÉ, DECEASED, LATE OF GOLDDENDALE, WASHINGTON, BY
VICTOR CELESTINE COUVRETTÉ, ADMINISTRATOR, OF SOUTH BEND, WASHINGTON.

MEANS FOR CARRYING SHIPS' LAUNCHES.

1,013,087.

Specification of Letters Patent. Patented Dec. 26, 1911.

Application filed July 15, 1911. Serial No. 638,665.

To all whom it may concern:

Be it known that I, VICTOR C. COUVRETTÉ, a citizen of the United States, and a resident of South Bend, in the county of Pacific 5 and State of Washington, administrator of the estate of CHARLES LOUIS COUVRETTÉ, deceased, late a citizen of the United States and late a resident of Goldendale, in the county of Klickitat and State of Washington 10 ton, who did in his lifetime invent a new and Improved Means for Carrying Ships' Launches, do declare that the following is a full, clear, and exact description of said invention.

15 The object of the invention is to provide means for carrying ships' launches, particularly launches to be used in emergencies, such as loss of the vessel.

Another object of the invention is to so 20 arrange the means for carrying the launch that the launch may be quickly and safely put into the water at any time and under any conditions. This end is attained by constructing in the ship a water-tight compartment, which runs thwartwise from side to 25 side, and which is provided at each end with doors forming the outer walls of the ship, which doors may be closed and hermetically seal the compartment when the launch is 30 not in use, and which upon opening the doors will permit the water to flow into the compartment so that the launch may then be water-borne therein and may be floated out of the compartment into the sea. This 35 permits the employment of a powerful launch or motor driven boat of large size, and to handle the same expeditiously and easily.

The invention involves various other features of major or minor importance, all of 40 which will be fully set forth hereinafter and particularly pointed out in the claims.

Reference is to be had to the accompanying drawings which illustrate as an example 45 the preferred embodiment of the invention, in which drawings—

Figure 1 is a partial side view of a ship to which the invention is applied; Fig. 2 is a cross section through the vessel showing 50 the compartment in which the launch is carried; Fig. 3 is a fragmentary longitudinal section of the vessel showing the water-tight compartment and the launch therein; Fig. 4 is a detail section showing the manner 55 of operating the doors to the water-

tight compartment; Fig. 5 is a detail view of one of the braces which are employed for said doors; Fig. 6 is a detail section of the jack by means of which the launch is held steadily in its compartment; and Fig. 60 7 is a detail section showing the gear for operating the lower sections of the doors of the compartments.

As shown in Figs. 2 and 3, the vessel is provided with a compartment 10 which extends transversely across the vessel from side to side. This compartment is watertight, and is provided with a pipe 11 for filling it, and a pipe 12 by which the water may be withdrawn. This pipe 12 passes to 70 any convenient point for the disposition of the water, which may be either a pump for expelling the water from the bilge of the vessel or a ballast tank in the bottom of the vessel. These pipes 11 and 12 are controlled 75 by gates 14 operated by screws 15, the upper ends of which are provided with wheels 16 facilitating the operation of the screws. The compartment 10 is entirely water-tight in its construction, and at each end it is 80 provided with an upper sliding door section 17 and a lower hinged door section 18. These door sections match to form a hermetic closure for the ends of the compartment. The lower section 18 of each 85 door is hinged at its bottom, as indicated at 19, and provided with chains 20 for limiting the downward or opening movement of the door section. For returning the door section to closed position curved racks 21 are 90 hinged to the door section, and their inner ends run through guides 22. With these racks are engaged gears 23 which as shown best in Fig. 7 have connection with ratchets 24 adapted to be operated by pawls 25 and 95 levers 26. The door sections 18 are adapted to be started out of the casement by means of screws 27, which operate in nuts 28 held stationary, as shown best in Fig. 7, and for operating the screws ratchets 29 are provided, with which ratchets pawls 30 and 100 levers 31 co-act. In order to open the door sections 18, therefore, the screws 27 should be operated until they engage the door sections and push them away from the casements, whereupon the door sections will fall to horizontal position and will then be 105 checked by the chains 20. The door sections 18 are returned by operating the gear 23 on the rack 21. 110

The upper door sections 17 match against the lower door sections 18 and slide in suitable guides constructed in the hull of the vessel. Said door sections 17 are adapted to drop by gravity into engagement with the sections 18, and they are raised by means of piston rods 32, the pistons (see the broken lines in Fig. 4) 33 of which operate in cylinders 34 secured in the vessel. To these cylinders steam-pipes 35 lead, so that steam may be applied at the desired moment to raise the door sections, as shown at the left-hand side of Fig. 2. For bracing the structure when the door sections 18 are closed, hinged braces 36 (see Figs. 4 and 5) are provided. These braces are adapted to swing down against the inner sides of the door sections and the adjoining edges of the walls of the ship, as shown in Fig. 4, and when the doors of the water-tight compartment are opened the braces are lifted up into the position shown in Fig. 2, by means of a weight 37, connected to the braces by cords 38. It is understood that the braces 36 are hinged or pivoted at their ends on suitable supports within the ship as indicated in Fig. 3, so that the braces can be swung up into inactive position as shown to the left in Fig. 2, or downward into active position as indicated to the right of Fig. 2 and in Figs. 3 and 4 to brace the structure when the door sections 18 are closed.

The launch is represented at 39 in the drawings. This launch should be as large as the size of the compartment or other considerations will admit, and constructed so that it may be used in rough weather. The launch is provided with jacks, shown in Figs. 2 and 6, for engaging its gunwales to steady the launch. Said jacks comprise (see Fig. 6) slides 40, operating in guides 41 and actuated by screws 42 having wheels 43 at their upper ends for manipulating them. A hinged stair 44 is provided to permit convenient entrance into the compartment, and this is connected with a tackle 45, enabling it to be raised at will.

In the use of the invention, supposing it is desired to send the launch out from the vessel, steam should be admitted to the cylinders 34 at the side from which it is desired to send out the launch, thus raising the door section 17 at said side. The screw 27 at said side should then be operated to start the dropping movement of the door section 18, said movement being checked by the chains 20. Previously, water should have been admitted to the compartment through the pipe 11, thus floating the launch, and as the door is opened the water will instantly find its level in the compartment. Steam or other motive power being ready to be instantly applied, the launch may then be taken by its own power out of the compartment into the open sea. After the launch

is sent from the vessel, the door sections may be again closed and the water pumped out of the compartment, if desired, or the doors may be kept opened until the launch returns. It will be observed that this invention avoids the necessity of lifting the launch by davits or other tackle, and it permits the employment of a far more powerful launch than any heretofore carried by marine vessels by means of which launch persons may be safely carried in extremely rough weather. If steam is employed as a motive power in the launch the boilers may be kept fully charged by steam from the boilers of the vessel itself, and as the launch is to be sent from the vessel the steam pipe connecting its boilers with the boilers of the vessel may be detached and fire started in the furnace of the launch boilers. If an engine of the internal combustion or explosive type is employed the necessary fuel should be kept at all times in the launch.

By placing the water-tight compartment thwart ship, a minimum of room is required for the launch, since the said launch may be passed directly through the side of the ship and at a right angle thereto, which would not be the case were the compartment arranged longitudinally. By this construction also more boats can be accommodated than when the chambers are placed lengthwise of the vessel, and each boat can be launched independently of the other, since they may be placed side by side and with an opening directly in front or behind.

Although reference is particularly made to launches, it is expressly understood that other marine vessels, such as submarines, may be carried by ship in the manner stated.

Having thus described the invention the following is claimed as new and desired to be secured by Letters Patent—

1. A marine vessel having a water-tight compartment therein, a hinged door and a sliding door for closing the compartment, said door being hinged to open downward, a screw for starting the hinged door, chains for limiting the downward movement of the door, and means for closing the door comprising a curved rack hinged thereto and guides for the rack, a pinion engaging the rack, a ratchet wheel rigid with the pinion, a lever provided with a pawl for manipulating the ratchet wheel, means for lifting the sliding door comprising cylinders within the vessel, pistons within the cylinders having rods connecting with the sliding door, and braces within the vessel for bracing the doors, said braces comprising U-shaped members having their body portions engaging the doors, and their arms pivoted within the vessel, and means for swinging the braces on their pivotal connection.

2. A marine vessel having a water-tight compartment therein, a hinged door and a

- sliding door for closing the compartment, said hinged door being hinged to open downward, a screw for starting the door, chains for limiting the downward movement of the door, means for closing the door, means for lifting the sliding door comprising cylinders within the vessel, pistons within the cylinders and having rods connected with the door, and braces within the vessel 5 for bracing the doors, said braces comprising pivotally mounted U-shaped members having their body portions engaging the doors.
3. A marine vessel having a water-tight compartment therein, a hinged door and a sliding door for closing the compartment, said hinged door being hinged to open 10
- 15
- downward, a screw for starting the door, chains for limiting the downward movement thereof, means for closing the door, 20 means for lifting the sliding door, and braces within the vessel for bracing the doors, comprising pivotally mounted U-shaped members whose body portions engage the doors. 25

In testimony whereof I have signed my name to this specification in the presence of two subscribing witnesses.
